AIR COOLING OXYGEN CIRCULATING
DEVICE

Randolph Lee, Maywood, Ill.

Application October 11, 1951, Serial No. 250,924

2 Claims. (Cl. 62—129)

1

This invention relates to an oxygen circulating device of a type that is generally used in regenerating the air supplied to a patient enveloped within an oxygen tent or hood. More specifically the invention relates to an improved oxygen circulating system of the mechanical refrigerated type having an improved air filtering construction embodied therein.

The primary object is to provide an improved construction in a mechanical air conditioned oxygen regenerating device.

Another object is to provide an oxygen circulating device having a mechanical cooling system including a removable filtering element so disposed with respect to the cooling coils of the device that any air which passes over the cooling coils is filtered prior to its contact with said coils.

A still further object is to provide an improved oxygen circulating device having a mechanical air conditioning unit, the unit including a plurality of cooling coils, the device including a blower for exhausting the air from an oxygen hood or tent and a filtering element so disposed in the device that the air passing over the coils is filtered prior to its contact with said coils.

Still another object is to provide an improved oxygen circulating device having a mechanical air conditioning unit in combination with a filtering element so disposed within the unit that the cooling coils of the unit remain free of lint and other matter that may be picked up in the air stream emanating from the hood.

These and further objects will become more readily apparent from a reading of the specification taken in connection with the accompanying sheet of drawing.

In the drawing:

Figure 1 is a cross sectional view in elevation of an oxygen circulating device as shown in use with an oxygen hood and supply;

Figure 2 is a sectional view taken substantially along the line 2—2 of Figure 1; and

Figure 3 is a perspective view of a filtering element.

Referring now to the drawing an oxygen circulating unit is generally indicated by the reference character 10. The unit 10 comprises a container 11 supported on caster wheels 12. A box or enclosure 13 is suspended within the container 11, this box having an opening 14 at its upper end. A box extension 15 is seated on the container 11 and projects upwardly with respect thereto.

The extension 15 is provided with a baffle 16 which divides the extension 15 into an inlet passage 17 and an outlet passage 18. The inlet

2

passage 17 and outlet passage 18 are respectively provided with openings 19 and 20 in communication with the interior of a hood or tent 21 which is suitably suspended from a support 22 supported on the extension 15. The hood 21 is adapted to enclose a patient lying on a bed 23 in a conventional manner.

The baffle 16 is provided with a portion 16' projecting into the box 13 to separate said box into an inlet chamber 24 in communication with the inlet passage 17, and an outlet chamber 25 in communication with the inlet chamber 24 and the outlet passage 18. A plurality of refrigerant cooling coils 26 are disposed in the chambers 24 and 25 immediately below the opening 14 of the box 13.

A horizontally extending section 27 is connected to the baffle 16, this section 27 defining the upper limits of the opening 19. The section 27 has a transversely extending angle 28 connected thereto. An angle 29 is connected across a top section 30 of the container 11. The angles 28 and 29 provide a backing for a filtering element 31 which is removably positioned in the inlet passage 17 over the opening 19. A reticulated member such as a screen or perforated plate 32 has its upper end connected to the extension 15 as indicated at 33 and to the section 30 as indicated at 34.

A blower 35 is positioned in the inlet chamber 24 immediately below the cooling coils 26. The blower 35 is connected for rotation with a shaft 36 journaled in bearings 37 mounted on the box 13. An electric motor 38 drives the shaft 37, the motor 38 being mounted in the container 11.

Refrigerant is supplied to the cooling coils 26 by means of a compressor 39 connected to a condenser 40 from which the liquid gas flows to a receiver tank 41. A conduit line 42 supplies the gas to an expansion valve not shown which delivers the refrigerant to the cooling coils 26 in a conventional manner. A return line 43 leads from the coils 26 to the compressor. The refrigerant system is only schematically shown and may be of conventional design including the necessary thermostats and control elements which need not be shown in the present invention.

Oxygen is supplied to the outlet passage by means of a conduit 45, opening into the passage as indicated at 46. The conduit 45 is connected to a conventional oxygen valve arrangement 47 mounted on an oxygen tank 48.

In conventional oxygen systems the cooling coils soon lose their efficiency since they become covered with lint and other materials which are

drawn from the hood. The interior of the passages and the chambers likewise become covered with this material requiring frequent cleaning and maintenance, thus necessitating the shut down of the machine. In order to avoid this problem, the present improvement contains a removable filter element that is placed in the intake passage 17, close to the cooling coils 26, so that all undesirable lint and other materials are filtered out before entering into the passages and the filtering chamber. The filter 31 in combination with the reticulated member 32 serve to clean the air as it returns to the circulating system, thus keeping the interior chambers and particularly the mechanical cooling coils in maximum efficiency operation. The element 31 can easily be replaced by removing the reticulated member 32.

Thus it can be seen that a new combination has been disclosed, the combination including an oxygen circulating system comprising a blower, mechanical refrigeration coils, and a filter disposed in such a position as to keep the cooling coils operating at maximum efficiency. It must be understood that changes may be made which do not depart from the spirit of the invention as disclosed nor from the scope thereof as defined in the appended claims.

What is claimed is:

1. An air cooling and circulating device adapted to be connected to a source of oxygen comprising, a container, a box positioned within said container, said box having an opening at its upper end, an extension projecting upwardly from the container, said extension being in communication with the opening of said box, a baffle positioned within the extension to divide the same into an inlet passage and an outlet passage, said baffle extending through the opening of said box into the box to divide said box into an inlet chamber and an outlet chamber, said chambers being in communication, said passages being open and being adapted to communicate with an enclosure, a plurality of cooling coils disposed in the inlet and outlet chambers immediately below the opening of said box, a blower in said inlet chamber disposed immediately below said coils in the inlet chamber, said blower being arranged to circulate air entering into said inlet passage over said cooling coils and through said outlet passage, a filter element disposed in said inlet passage substan-

tially adjacent said cooling coils in the inlet chamber, mechanical refrigeration means connected to said cooling coils, and a reticulated member disposed over said opening of the outlet passage and over the filter element disposed in the inlet passage.

2. An air cooling and circulating device adapted to be connected to a source of oxygen comprising, a container, a box positioned within said container, said box having an opening at its upper end, an extension projecting upwardly from the container, said extension being in communication with the opening of said box, a baffle positioned within the extension to divide the same into an inlet passage and an outlet passage, said baffle extending through the opening of said box into the box to divide said box into an inlet chamber and an outlet chamber, said chambers being in communication, said passages being open and being adapted to communicate with an enclosure, a first plurality of cooling coils disposed in the inlet chamber on one side of said baffle, a second plurality of cooling coils disposed on the other side of said baffle in said outlet chamber immediately below the opening of said box, a blower in said box disposed immediately below said coils, said blower being arranged to circulate air entering into said inlet passage over said cooling coils and through said outlet passage, a removable filter element disposed in said inlet passage substantially adjacent said cooling coils in the inlet chamber, mechanical refrigeration means in said container for supplying refrigerant to said cooling coils, and a removable reticulated member disposed over said filter element disposed in the inlet passage.
